RICHARD T. McGEE, OF WHEELING, WEST VIRGINIA.

BLANK-CASTING MACHINE.

Application filed June 12, 1926. Serial No. 115,489.

This invention relates to blank or slug casting machines, and the primary object thereof is to provide a machine for producing the small slugs or blanks employed in 5 the manufacture, by extrusion, of collapsible metal tubes.

A further object of the invention is to provide a machine by means of which may be produced blanks of uniform thickness, as 10 distinguished from blanks having concavities in their upper sides or faces. Heretofore, the sprue has been sheared from the blank immediately following completion of the molding operation and while the metal 15 was still in its plastic or soft condition, and the result of this has been to form central concavities or irregularities in the upper faces of the blanks or slugs, since such shearing of the metal while hot causes the sprue 20 to carry with it, or to tear-off, some of the metal which belongs in the blank.

The present invention thus aims to permit the sprue to remain undetached until the metal has become thoroughly cooled and 25 set, and also to feed to the blank metal from the sprue during contraction of the blank, thereby to produce a blank of uniform thickness throughout.

The invention further aims to provide a 30 machine of this type which effects clean cutting of the sprue so as to assure that the blanks shall have truly flat upper faces.

Still further, the invention aims to provide 35 novel means for ejecting the blank or slug and novel means for disposing of the sprue.

With these and other objects in view, the 40 invention resides in the novel features of construction and arrangement of parts which will hereinafter be fully described, reference being had to the accompanying drawings, in which—

Figure 1 is a top plan view of the invention;

Figure 2 is a front elevation of the same;

Figure 3 is a horizontal section on line 45 3—3, Fig. 2;

Figure 4 is a detail plan view of the cam plate;

Figure 5 is a similar view of the guide 50 disk;

Figures 6, 7 and 8 are enlarged detail sections on lines 6—6, 7—7, and 8—8, respectively, of Fig. 1;

Figure 9 is an enlarged detail plan view of 55 one of the bottom molding plates;

Figure 10 is a detail view of one of the sprue blocks;

Figure 11 is an enlarged detail plan view 60 of one of the molding and sprue shearing plates;

Figure 12 is an enlarged side elevation of a fragmentary portion of the table, showing a block pivoted thereon.

Referring to said drawings, 1 indicates a portion of the frame of a metal melting and 65 feeding mechanism of any appropriate construction. A substantially L-shaped bracket 2 is secured to the base of the frame and has a vertical shaft 3 journaled therein. A ratchet wheel 4 is keyed on said shaft 3 and 70 has its teeth engaged by a pawl 5 pivoted on one end of an L-shaped arm 6, which is mounted for free rotary movement on said shaft 3. The other end of the arm 6 has 75 pivotal connection with an operating rod 7 which may be reciprocated in any suitable manner.

A circular cam plate 8 is rigidly mounted 80 in horizontal position on the upper end of the bracket 2 by means of screws 8', said plate 8 being formed with a continuous outer cam groove 9 and an inner cam groove 10, and, further, being formed with two relatively spaced openings 85 11 and 12 at points more or less closely adjacent to its peripheral edge. A circular guide disk 13 is formed with a centrally located square hole 14 in which is received a squared upper end portion 3a of the shaft 3. Thus mounted, provision is made for rotary 90 movement of the disk 13 with the shaft 3. Slidably mounted in substantially rectangular openings 16 provided therefor in, and extend radially of, the plate 13 are the bottom forming plates 15 of a mold, each thereof being provided with a roller 17 which engages in the inner groove 10 of the cam plate 8. The plates 15 are further provided intermediate their ends with elongated slots 18 and adjacent to their outer ends with 95 openings 19. Combined molding and shearing plates 20 are superimposed on said plates 15, each thereof provided with a roller 21 which extends through the slot 18 of the underlying plate 15 and into the outer cam 100 groove 9 of the cam plate 8. Said plates 20 are further provided with openings 22 of the same diameter as the openings 19 of said plates 15.

A top plate 23 is superimposed on the 110

plates 20 and has a central squared opening which is received over the square upper end 3^a of the shaft 3. Sprue blocks 24, pivotally mounted on blocks 25 which are fixed on the periphery of the plate or table 23, have their inner faces conforming to the peripheral curvature of the latter and have in said faces recesses 26 which constitute sprue openings. Springs 27 are employed to tension the sprue blocks for normally holding same in closely seated relation to the periphery of the table, as shown in Fig. 10 of the drawings. It will be noted that, as shown in Fig. 1, there is one sprue block 24 for each of the pairs of relatively slidable plates 15 and 20 located in the openings 16 of the disk 13. Each block 24 carries on its top face adjacent to its free end a roller 28 which is engageable with the outer edge or face 29' of a stationary cam 29 which is suitably mounted in stationary overhanging relation to the table 23, but which is herein shown as attached at 30 to the cam plate 8. As shown in Fig. 7, a vertically depending knock-off pin 31 is carried by one end of a lever 32 which is pivoted intermediate its ends to a standard 34 carried by the frame 1, as shown at 33. A coil spring 35 encircling the pin 31 is interposed between a collar 36 fixed on said pin and the cam plate 37 through which said pin 31 is vertically movable, said cam plate 37 being mounted on the plate 8 and presenting an inwardly directed cam edge to the roller 28. The rear end of said lever 32 occupies overlying seated relation to the upper end of a vertical rod 38 which is vertically slidable in the standard 34. The lower end of the rod 38 is seated upon the end of a lever 39 which is pivoted at 40 to the frame 1 and which is arranged to be rocked by any suitable means (not shown).

In practice, since the ratchet 4 has a number of teeth corresponding to the number of pairs of plates 15 and 20, each forward reciprocating movement of the operating rod 7 acts to advance the disk 13 and the top plate 23 relative to the stationary plate 8 throughout a definite distance, as 45°, and such movements successively present the outer ends of the various radially shiftable plates 15 and 20 in registering alinement with the outlet of a pouring spout 41 by which the molten metal for casting is delivered. In the charge receiving position, the plate 15 is so disposed relative to the overlying plate 20 that an unapertured portion thereof underlies and closes the lower end of the blank opening 22 of said plate 20, thus, in effect, forming a mold bottom. The pair of plates 15 and 20, following reception of a charge of molten metal, effected through the gate constituted by the recess 26 in the adjacent sprue block 24, is advanced by intermittent movements through-

out about 225° before relative movements of said plates is initiated, thus to permit the metal to cool to the required extent. The roller 21 then enters an outwardly offset portion 9^a of the cam groove 9 provided in the cam plate 8, by which said plate 20 is gradually shifted outward in its guide opening 16 of the disk 13 until the mold opening 22 thereof registers with the corresponding opening 19 in the plate 15, which latter then is also alined with the blank-delivery opening 11 of the cam plate. In this movement from the charge receiving and cooling position, shown in Fig. 6, to the position of the parts shown in Fig. 7, effected by traverse 80 of the roller 21 in the offset portion 9^a of the cam groove 9, shearing of the sprue, contained in the gate 26, from the upper face of the partially cooled blank is effected.

During said outward movement of the plate 20, in which shearing off of the sprue is effected, as aforesaid, the roller 28 of the sprue block is firmly engaged by the cam 37, thus to maintain said block against movement for insuring the making of a clean cut 90 in such shearing. At this time the lever 39 is rocked to raise the rod 38 and lift the tail of a lever 32, thereby depressing the front end of lever 32 and therewith the knock-out pin 31, thus positively ejecting the molded and sheared blank through openings 19, 22 and 11. Upon continued movement of the carrier, the roller 28 of the sprue block 24 moves into engagement with the cam 29, as shown in Fig. 8, whereby the sprue block is 100 swung away from disk 23, as shown in Fig. 8, thereby releasing the detached sprue. The sprue at this time is located in register with the opening 12 of the cam disk 7, and drops by gravity through said opening.

From the foregoing it will be seen that an intermittent movement is provided, and that, following introduction in a mold of a charge of molten metal, the latter is allowed to stand for a length of time sufficiently long to become chilled and set, whereupon the sprue is sheared therefrom and the blank ejected.

Further, it will be noted that the sprue remains undetached throughout the period 115 of contraction of the blank due to cooling, so that additional metal therefrom may be furnished as required to produce uniformity of thickness in the blanks or slugs, and also to insure the production of a smooth cut in 120 effecting detachment of the sprue.

As shown in Figs. 6, 7 and 8 the outer wall of the recess 26 is inclined downwardly and inwardly for facilitating clean shearing of the sprue.

What is claimed is—

1. In a blank casting machine, a pair of mold members, one of said members having a blank molding space therein and the other being adapted in one position to form a bot. 130

tom for said mold space, means to feed molten metal to said space, means to shift the first mentioned member relative to said feeding means for effecting detachment of the sprue from the blank formed in said space, and means to shift said bottom forming member to a position wherein said blank remains unsupported.

2. In a blank casting machine, feeding means, molding means having an open bottom, movable means to close the bottom of the molding means, means for ejecting molded blanks from the mold, and means to relatively shift the molding means and the bottom closing means so that, when the molding means occupies registering relation to said feeding means, the closing means will occupy closing position, and so that, when said ejecting means is approached, said molding means is moved relative to said feeding means to effect shearing of the sprue from the blank, and when the molding means registers with the ejecting means the closing means will occupy a position in which the bottom of the molding means is open for releasing the blank.

3. In a blank casting machine, a mold comprising relatively shiftable plates, a mold carrier, means to drive said carrier, means to feed molten metal into the mold, blank ejecting means located at a distance from the feeding means, and means to actuate said plates for shearing the sprue from the blank before the mold reaches the ejecting means.

4. In a blank casting machine, a mold comprising relatively shiftable members, a carrier for said mold, means to feed molten metal into the mold, means for shifting one of the mold members to open and close the mold space in the other member, and means

to actuate the last mentioned member relative to the feeding means for detaching the sprue.

5. In a blank casting machine, molds, a mold carrier, sprue blocks movably carried by the carrier, means to effect movement of the molds relative to the blocks to shear the sprue, and means to operate the blocks to release the sprue.

6. In a blank casting machine, a plurality of molds, a mold carrier, sprue means carried by the carrier, and means to actuate the molds to shear the sprue from the blanks while in the molds.

7. In a blank casting machine, a movable mold, a movable bottom for the mold, sprue means, and means to move the mold to shear the sprue and to move the bottom to release the blank.

8. In a blank casting machine, a plurality of molds, a mold carrier, movable sprue blocks carried by the carrier, means to actuate the molds to shear the sprue from the blanks formed in the molds, means to hold the sprue blocks against movement during shearing of the sprue, and means to move the blocks to release the sprue after shearing thereof.

9. In a blank casting machine, a carrier, movable molds carried by the carrier, sprue means carried by the carrier, and means to move the molds to shear the sprue.

10. In a blank casting machine, a carrier having sprue means, movable molds carried by the carrier, movable bottoms for the molds, and means to move the molds to shear the sprue and to subsequently move the bottoms to release the blanks.

In testimony whereof, I affix my signature.

RICHARD T. McGEE.
